UNITED STATES PATENT OFFICE.

CHARLES F. MILLER, OF MOORE, PENNSYLVANIA, ASSIGNOR TO WESTINGHOUSE ELECTRIC AND MANUFACTURING COMPANY.

SIDE-WALL TUYÈRE.

Application filed April 2, 1923. Serial No. 629,538.

To all whom it may concern:

Be it known that I, CHARLES F. MILLER, a citizen of the United States, and a resident of Moore, in the county of Delaware and State of Pennsylvania, have invented a new and useful Improvement in Side-Wall Tuyère, of which the following is a specification.

This invention relates to tuyère plates of the character employed in high temperature furnaces, and particularly to side wall air-cooled tuyère plates for such furnaces and it has for an object to provide a tuyère plate of the character designated which shall have heat dissipating surfaces greatly in excess of its heat absorbing surfaces, and which shall have increased strength to resist distortion due to excessive and uneven heating. It is a further object of my invention to provide a metal tuyère plate presenting a highly refractory inner surface to the furnace, and provided on the outer side with strips of steel embedded in the metal and serving to assist in the dissipation of the heat absorbed by the plate and also serving to reinforce the plate against distortion or warping.

These and other objects of my invention, which are made more manifest in the further description thereof, may be attained by the employment of apparatus illustrated in the accompanying drawing in which: Fig. 1 is a view in vertical section through a furnace side wall tuyère embodying the present invention; Fig. 2 is a view in elevation of a side wall tuyère plate; and Fig. 3 is a fragmentary view in transverse section of the tuyère plate.

In the drawing I show a side wall tuyère plate 10 mounted on a bracket 11 which is supported on the wall air box 12 of a conventional stoker furnace.

The tuyère plate 10 is preferably constructed of cast iron and provided with a receding edge flange 14, forming a seat for an adjacent tuyère plate, a base lug 15 and a top hook 16, each engaging the bracket 11 to retain the plate in position.

In casting the tuyère plate 10, steel strips 18, which are relatively thin and substantially equal in length of the tuyère are arranged in parallel spaced relation in the mould in such manner that, when the molten iron is poured, the steel strips are partially embedded in the tuyère plate. The major portion of each of the steel plates, however,

preferably protrudes beyond the surface of the casting. The number of the steel strips and the extent of their protruding surfaces may be equal to two or three times the plane heat absorbing surface of the exposed face 60 of the tuyère. The tuyère plates are perforated, as at 19, between the reinforcing steel strips, the perforation being preferably formed by the provision of cores in the mould at time of casting. 65

The high maintenance cost of high duty furnaces is large; due to the necessity for frequent replacement of burned out and distorted parts. Tuyère plates are more frequently removed than other parts of the 70 furnace and side wall tuyères are subjected to extreme heats both from incandescent coal and highly heated furnace gases. From the foregoing, it is apparent that a tuyère plate having a longer life than those at the 75 present time employed is provided. The greatly increased heat dissipating area of the present tuyère, and the reinforcement of the plate against distortion because of the many steel beams embedded in the plate, 80 contribute to produce a plate which has a longer life and which is more economical in the long run than similar tuyère plates as at present constructed.

While I have shown my invention in but one form, it will be obvious to those skilled in the art that it is not so limited, but is susceptible of various other changes and modifications, without departing from the spirit thereof, and I desire, therefore, that only 90 such limitations shall be placed thereupon as are imposed by the prior art or as are specifically set forth in the appended claims. 85

What I claim is:

1. A side wall tuyère for stoker furnaces 95 comprising a perforated metal plate and a plurality of steel strips partially embedded in the metal plate and partially protruding from the plate.

2. A side wall tuyère comprising a perforated cast iron plate, and a plurality of steel strips partially embedded in the cast iron plate and partially protruding from a face of the plate. 100

3. A side wall tuyère comprising a perforated cast iron plate, and a plurality of relatively thin steel strips partially embedded in the iron plate and partially protruding from a face of the plate. 105

4. A side wall tuyère comprising a perforated 110

rated cast iron plate, and a plurality of thin steel strips each having an edge portion embedded in the iron plate, the major portion of each strip protruding from a face of the plate.

5. A side wall tuyère for stoker furnaces comprising a cast metal plate, and a plurality of parallelly disposed steel strips partially embedded in the metal of the plate, the major portion of each strip protruding from a face of the plate.

6. A side wall tuyère for stoker furnaces comprising a cast iron plate, and a plurality of parallelly disposed steel strips of 15 slightly less length than the height of the plate partially embedded in the metal of the plate, the major portion of each strip protruding from a face of the plate.

7. A side wall tuyère for stoker furnaces 20 comprising a cast iron plate, and a plurality of parallelly disposed steel strips of slightly less length than the height of the plate partially embedded in the metal of the plate, the major portion of each strip pro-

truding from a face of the plate, said plate 25 having perforations disposed between the steel strips.

8. A side wall tuyère for stoker furnaces comprising a perforated cast iron plate having one side adapted for exposure to 30 the heat of the furnace and the other side adapted for exposure to cool air, and a plurality of steel strips partially embedded in the casting and partially protruding from the side of the casting adapted for exposure 35 to air.

9. A side wall tuyère for stoker furnaces comprising a perforated cast iron plate having one side adapted for exposure to the heat of the furnace and the other side 40 adapted for exposure to cool air, a plurality of thin steel strips partially embedded in the casting and protruding from the side of the casting adapted for exposure to air.

In testimony whereof, I have hereunto 45 subscribed my name this 29th day of March, 1923.

CHARLES F. MILLER.
